UNITED STATES PATENT OFFICE.

MATHER W. SHERWOOD, OF FRANKLIN, PENNSYLVANIA, ASSIGNOR TO CHICAGO PNEUMATIC TOOL COMPANY, OF CHICAGO, ILLINOIS, A CORPORATION OF NEW JERSEY.

DRILL.

1,098,690.

Specification of Letters Patent.

Patented June 2, 1914.

Application filed September 30, 1913. Serial No. 792,557.

To all whom it may concern:

Be it known that I, MATHER W. SHERWOOD, a citizen of the United States, residing at Franklin, Venango county, Pennsylvania, have invented certain new and useful Improvements in Drills, of which the following is a specification.

My invention relates in general to drilling machines such as rock drills and more particularly but not necessarily of that type commonly known as a stoper and the object thereof is to provide a simple, efficient and reliable machine of this character.

My invention relates more particularly to means for feeding the motive fluid directly and initially to the feed device and subsequently to the engine past a loaded valve, in order to insure the drill being brought into position against the work such as the rock before the drilling operation begins. When sufficient pressure has been supplied to the feed device said valve is opened and the drilling operation begins.

Other novel and advantageous features of construction and operation in my new form of drill will be apparent from the description hereinafter given.

In the drawing Figure 1 is a central longitudinal sectional elevation of a drill embodying my invention; Fig. 2 a sectional elevation on the line 2—2 of Fig. 1; Fig. 3 an elevation looking in the direction of the arrows 3—3; Fig. 4 a similar view but looking in the opposite direction, that is in the direction of the arrows 4—4 of Fig. 1.

Referring to the present embodiment of my invention as herein shown, the same comprises three main parts, to wit the engine of the drill, the feed device thereof arranged in axial alinement with the engine, and a head block connecting the engine and feed device and by preference forming a part of the feed device.

My present invention concerns more particularly the feed device and the valve mechanism intermediate the same and the engine. The latter, as to its details, forms no part of my present invention and hence the same will be described only in a general way.

The engine part of the machine consists of a cylinder 1, piston 2, impact piece 3, drill socket 4 and distributing valve mechanism. The cylinder is provided with two similar inlet passages 5 communicating with

the source of motive fluid indirectly through 55 the feed device in a manner hereinafter explained. Between these inlet passages is formed the distributing valve chamber communicating therewith by ports 7 and with the rear end of the piston chamber by port 60 8. The valve 9 operates in a valve cage comprising two valve seats 10 and 11 and sleeve 12 which has inlet ports 13 communicating with port 7. The two seats have ports 14 and 15 controlled by the valve, port 65 14 communicating with passage 16 leading to the front end of the piston chamber through port 17. A coiled spring 18 is interposed between the seat 11 and a plug 19 extending into the valve chamber and 70 held in place by the head block 20. In addition to the ports mentioned the cylinder 1 has exhaust ports 47 and groove 48.

Referring next to the head block and subsequently to the feed device, this block is 75 adapted to form the head of the cylinder and also to hold the plug 19 in place, particularly when the latter is not screw-threaded. To this end this block is provided with a cylindrical boss 20^a fitting into 80 the piston chamber and consequently interlocking with the cylinder. It is also provided with a series of ports 21 communicating with cylinder exhaust ports herein-after described. The block is also provided 85 with a central bore or chamber 22 for the passage of motive fluid to the engine through a wide port 23 communicating with the ports 5. This port 23 also receives at its central portion the diametrical rib 19^a of 90 the plug thereby holding such plug in position and serving as means for interlocking the block with this portion of the engine structure. Within the bore of the block is arranged a loaded valve comprising a piston 24 movable therein and held to upper 95 position when viewed as in Fig. 1 by means of the coiled spring 25 which loads the valve with from 20 to 25 pound pressure which is the desirable one in practice. This coiled 100 spring bears at its lower end against an adjustable nut or plug 26 screwing into the lower end of the block and after passing through the hollow piston it bears against the bottom of the socket formed by the hollow piston stem. At its upper end this stem carries a head 27 having ports or openings 105 therethrough and constituting a valve gov-

erning the passage of the motive fluid to the valve chamber through the port 23, this head being movable to open and close said port. The motive fluid is supplied through the feed device and the same enters the chamber 22 through the port 28.

The feed device may be described in general as consisting of telescopic cylinders, with the result that the air admitted to them extends them and causes a feeding of the drill as the drilling operation proceeds. As herein shown the head block itself constitutes one of the main parts of these telescoping cylinders and in fact constitutes the movable one or rather the piston portion of such feed device. The head block is provided with a tubular extension 29, preferably integral therewith and comprising the inner section of the inner cylinder or what will be hereinafter referred to as the piston of the feed device. To this inner section is secured in suitable manner a second tubular section 30 closed at its outer end by a cap or thimble 31 secured to the section 30. The section 30 is provided with one or more ports 30^a for the passage of the motive fluid into the interior of the piston. By preference I provide this hollow piston with means for lubricating the motive fluid as it passes therethrough on its way to the engine. To this end I provide a sleeve 32 screwing at its inner end into the port 28 of the block 20 and extending axially of the piston. This sleeve has a flange 32^a at its outer end adapted to seat against the outer beveled edge of the inner section 29 of the piston. In this manner there is formed an annular chamber 33 for the reception of a supply of lubricant which is fed through one or more holes 34 in the sleeve to the interior thereof, that is in the path of the motive fluid as it passes through the feed device. It is preferred to employ in this lubricant or oil chamber a wick such as a lamp wick 35 so that with a minimum quantity of lubricant the proper supply of the lubricant through the holes 34 is possible. The lubricant chamber has a filling opening which is closed by the screw plug 36.

50 The outer cylinder or stationary part of the feed device is also preferably made of several sections. The outer end section 37 is tubular and closed by an end piece 38 carrying a suitable point 39. The inner end of the section 37 is secured to a section 40 having an internal circular flange 40^a between which and an inner section 41 is clamped suitable packing 42 bearing against the sides of the piston of the feed device. This inner section 41 is held in place by means of the coupling ring 43 screwing upon the section 40 and having a shoulder bearing against a corresponding shoulder on the section 41. In order to hold the feed device in its closed or innermost position I prefer to provide

the dog 44 which engages the coupling ring 43 as seen in Fig. 1.

The outer cylinder or cylinder proper is provided with an inlet 45 with which the air hose having a suitable throttle (both not shown) are arranged to communicate. The motive fluid passes from the inlet 45 to the space between the cylinder and its piston, passes through the ports 30^a into the piston itself, through the longitudinal bore of the sleeve 32 and into the chamber 22. The first effect of the motive fluid is to extend the feed device and thereby position the machine before the drilling operation can proceed for, as will be understood from the preceding description, the port 23 is now closed by the valve 27 and no motive fluid can pass to the engine. After the machine is thus positioned and when the motive fluid is of such pressure as to overcome the load of the spring 25 the motive fluid will move the piston 24 and the valve 27 downwardly thereby opening the port 23 and admitting the motive fluid to the engine. It will be understood that the motive fluid after passing through the feed device as explained passes through the port 28 and enters the piston chamber 22. The fluid passes upwardly through the ports and passages 27^a in the head 27 to the space thereabove and simultaneously the fluid presses downwardly upon the upper face of the piston head 24, with the result that such head together with the head 27 is moved downwardly (speaking in reference to Fig. 1) against the tension of the spring 25. Normally, as seen in Fig. 1, the piston head 27 closes the port 23 but when thus moved downwardly it will clear such port and thereby admit the motive fluid to the ports 23 and 25 and thence to the engine. When the supply of motive fluid is shut off the spring will force the piston heads upwardly and close the port 23. The spring is adjusted to such a tension which is regulated by the adjusting plug 26 as necessitates the accumulation of a predetermined amount of pressure in the feed device, say a pressure of twenty to twenty-five pounds, before it will be sufficiently compressed to allow of sufficient movement of the valve to uncover the port 23 leading to the valve chamber of the drilling engine as above explained. The chamber 22 is closed at its upper end by means of the rotating handle 46 whose inner end screws into the block 20 and serves as a screw plug. By means of this handle the drill may be supported and guided by hand.

The head block and the cylinder are connected or clamped together in any suitable manner. In the present instance, the cylinder is provided with pairs of ears 49 and the head block with corresponding pairs of ears 50, through which ears pass the clamping bolts 51.

I claim:

1. In a tool of the class described, the combination of a drilling engine, a feed device connected therewith, means for feeding the motive fluid direct to said device, means of communication between the engine and air feed device, and a loaded valve interposed in said communication.

2. In a tool of the class described, the combination of a drilling engine, a feed device, a connecting member located between the engine and device and having passage for the motive fluid from said device to the engine, means for feeding the motive fluid direct to said device, and a loaded valve interposed in said passage.

3. In a tool of the class described, the combination of a drilling engine, a feed device therefor comprising telescoping cylinders, a connecting member connected on one side with the engine and on the other side with one of the telescoping cylinders, means for feeding the motive fluid direct to said device, said connecting member having a motive fluid passage, and a loaded valve interposed in said passage.

4. In a tool of the class described, the combination of a drilling engine, a feed device therefor, a head block connected on one side with the engine and on the other side with the feed device, means for feeding the motive fluid direct to said device, said block having a motive fluid supply passage, and a loaded valve in said passage comprising a spring pressed piston exposed on one side to the motive fluid, and a piston head connected with the piston and governing said passage to the engine.

5. In a tool of the class described, the combination of a drilling engine, a feed device therefor, a head block connected on one side with the engine and on the other side with the feed device, means for feeding the motive fluid direct to said device, said block having a motive fluid supply passage, and a loaded valve in said passage comprising a spring pressed piston exposed on one side to the motive fluid, said passage terminating in a port communicating with the engine, and a piston head connected with the piston

and having ports therethrough, said piston head governing said port.

6. In a tool of the class described, the combination of a drilling engine, a feed device therefor, a head block connected on one side with the engine and on the other side with the feed device, means for feeding the motive fluid direct to said device, said block having a motive fluid supply passage, and a loaded valve in said passage comprising a spring pressed piston exposed on one side to the motive fluid, said passage terminating in a port communicating with the valve chamber of the engine, and said engine including a plug closing one end of the valve chamber and having a portion interlocked with said port.

7. In a tool of the class described, the combination of a drilling engine, a feed device therefor comprising telescoping cylinders, and means for feeding the motive fluid direct to the cylinders and thence to the engine, the inner cylinder having a head portion provided with an internal sleeve connected therewith at one end and seating thereon at its other end, said sleeve forming with said inner cylinder an annular oil chamber and having an outlet to the interior of the inner cylinder and in the path of the motive fluid.

8. In a tool of the class described, the combination of a drilling engine, a feed device, a connecting member located between the engine and said device and having a passage from said device to the engine, the air feed device comprising telescoping cylinders the inner one of which is connected to said member and provided with an internal conical seat, a sleeve located within the inner cylinder and secured to said member and seating on said seat, the sleeve forming with the inner cylinder an annular oil chamber and having an oil port to the interior of the sleeve which communicates with said passage, and means for supplying the motive fluid direct to the air feed device.
